UNITED STATES PATENT OFFICE.

OTUS PICKELSMIMER, OF GREENVILLE, SOUTH CAROLINA.

TROUSERS CREASER AND FORMER.

1,406,891.

Specification of Letters Patent. Patented Feb. 14, 1922.

Application filed April 6, 1921. Serial No. 459,020.

To all whom it may concern:

Be it known that I, OTUS PICKELSMIMER, a citizen of the United States, residing at Greenville, in the county of Greenville and 5 State of South Carolina, have invented certain new and useful Improvements in Trousers Creasers and Formers; and I do hereby declare the following to be a full, clear, and exact description of the invention, such as will enable others skilled in the art to which it appertains to make and use the same.

The present invention relates to improvements in ironing machines and it consists in 15 certain improvements over my prior Patent No. 1,354,438, granted September 28, 1920.

An object of the invention is to provide an improved ironer and molder for overalls, trousers and the like in which a desired pressure will at all times be exerted to the end 20 that an effective and permanent crease may be imparted to the garment.

Another object of the invention resides in providing for the removal of any back pressure in the machine which tends to decrease 25 its effectiveness.

A still further object of the invention resides in providing a machine having an automatically expansible head which may be contracted in the act of placing the garment 30 over the casting but which is subsequently automatically distended to hold the creasing wires taut and in a proper position to impart the crease to the garment.

With the foregoing and other objects in view, the invention will be more fully described hereinafter and will be more particularly pointed out in the claims appended hereto.

40 In the drawings, wherein like symbols refer to like or corresponding parts throughout the several views,

Fig. 1 is a view in side elevation of an improved ironing machine constructed according to the present invention;

Fig. 2 is an end view thereof.

Fig. 3 is a vertical sectional view of the device;

Fig. 4 is a top plan view thereof;

50 Fig. 5 is an enlarged fragmentary vertical sectional view through the head portion of the machine in an expanded condition;

Fig. 6 is a similar view with the parts contracted;

55 Fig. 7 is an enlarged top plan view of the head; and

Fig. 8 is a side view of a detail.

Referring more particularly to the drawings, 1 and 2 designate the legs which support the stand or platform 3 to which the basal flange 4 of the hollow casting 5 is secured as by a bolt 6 or other suitable fastening means. As in my prior patent, steam is employed to enter through the lower open base of the casting 5 and after circulating therethrough to be exhausted, but I prefer to remove the partition which divided the casting 5 in accordance with the construction of the prior patent aforesaid and to lead the steam induction pipe 7 upwardly through the hollow casting 5 to a point near the top thereof at one side, where the steam is liberated. As the steam cools and condenses, the water of condensation will flow down the side walls of the casting 5 and may seek an exit through the drain pipe 8.

I provide an air outlet pipe 9 which also traverses the major portion of the height of the casting 5, having its upper end at the side of the casting opposite to that of the steam induction pipe 7. The purpose of this pipe 9 is to allow of the escape of the trapped air to the end that any back pressure will be relieved and allow the steam to act effectively in bringing the casting up to a suitably high heat.

In accordance with the present improvement two crease wires 10 and 11 are employed, the lower ends of which project through the platform 3 where they are provided with winged nuts 12 and 13 and with coil springs 14 and 15 disposed between the nuts and the under side of the platform.

The function of the coil springs is to constantly keep the creasing wires 10 and 11 in a taut condition and under a suitable resilient tension. The upper ends of these wires are bent upon themselves and downwardly to provide extremities 16 and 17 which fit within the openings 18 and 19 made therefor in a pair of cooperating expansible head plates 20 and 21 which are disposed crosswise in the transversely slotted head 22 of the casting 5. The head is provided with rollers 23 and 24 near the lower portion of the transverse slot to receive cut out parts 25 and 26 of the plates. The plates thus roll back and forth on the rollers 23 and 24 which eases to a considerable extent their movement. Stops 27 and 28 are provided on the plate 20 at opposite sides of the cut out portion 25 in order to limit the extent of the inward and outward movement; and in a similar way like

stops 29 and 30 are provided on the companion plate 21.

The plate 20 is cut away as at 31 to receive the projecting tongue 32 on the plate 21, which tongue is formed with a horizontally elongated slot 33 having a sliding movement on a pin 34 projecting outwardly from the cut away part 31 of the plate 20. In a similar way a pin 35 projects out from 10 a cut away part 36 on the plate 21 and occupies a horizontally elongated slot 37 in the tongue 38 of the plate 20. The plates thus overlap and slide on each other.

Beneath the tongues and carried by the 15 stops 27 and 29 are studs 39 and 40 projecting toward one another and receiving a sleeve 41 about which is coiled a spring 42 tending to keep the plates apart or in the expanded condition shown in Fig. 5. The 20 head is suitably recessed as indicated at 43 in Fig. 7 to accommodate this spring and sleeve. Furthermore the side edges of the plates 20 and 21 are formed with grooves 44 and 45 for the upper ends of the creasing 25 wires 10 and 11.

In use, the device is normally in the condition shown in Figs. 1 and 5 with the head plates expanded. Steam is let in through the induction pipe 7 under suitable control 30 and the casting 5 brought up to a suitable temperature. More or less air may be allowed to escape through the pipe 9 and water of condensation through the drain 8, these various pipes being controlled in accordance with varying conditions.

The garment sleeve or leg to be pressed is then drawn over the head, and as a consequence the plates 20 and 21 will be automatically moved together for instance to the 40 contracted position shown in Fig. 6. In so doing the coil spring 14 and 15 will contract to allow of this movement of the plates, at the same time keeping the wires 10 and 11 taut, and when the pressure is removed 45 from the plates the coil spring 42 will cause them to again expand and in like manner the coil springs 14 and 15 will also expand against the nuts 12 and 13 so that in all cases the wires 10 and 11 will be kept under 50 a proper tension. After the garment has remained on the form or casting 5 for a suitable length of time it is removed and will be found to have a very effective and permanent crease therein.

The head plates 20 and 21 may readily be lifted out of the slotted head at any time, the wires 10 and 11 being of course first removed by unscrewing the nuts 12 and 13, and the heads may be adjusted, repaired or 60 replaced. The device provides for the pressing of garments of varying sizes and throughout a large range of widths.

It is obvious that various changes and modifications may be made in the details 65 of construction and design of the above

specifically described embodiment of this invention without departing from the spirit thereof, such changes and modifications being restricted only by the scope of the following claims.

What is claimed is:—

1. A garment former and creaser comprising a heated form, creasing means at the 70 outsides of the form, and an expandible head exterior to the form connected to said creasing means, substantially as described.

2. A device of the kind described comprising a heated form, creasing means at the 75 sides of the form, an expandible head at the top of the form connected to said creasing means, a resilient anchoring means at the base of said creasing means, substantially as described.

3. A device of the kind described comprising a form, means to controllably heat 80 the form, creasing means at the sides and independent of the form, and an expandible head connected to said creasing means, substantially as described.

4. A device of the kind described comprising a hollow imperforate form, heating means adapted to introduce a heating medium into the upper end of said hollow form, means for allowing of the escape of air 85 from the upper and closed portion of the form, and adjustable creasing means at the sides of the form, substantially as described.

5. A device of the kind described comprising a form having a slotted head, a pair of companion plates having overlapping parts 90 slidable upon one another and adapted to project beyond the sides of the frame, means to yieldably hold the plates in an extended position, and creasing means attached to the plates and passing down outside of the form, 95 substantially as described.

6. A garment former and creaser comprising a form having a transversely slotted head, rollers in the slotted head, a pair of companion plates slidably on said rollers 100 and having stop means to engage the rollers, overlapping parts on the plates, and means to normally hold the plates apart, substantially as described.

7. A garment former and creaser comprising a form having a transversely slotted head, rollers therein, plates having cut away 105 parts lying upon said rollers and provided with stop portions at opposite sides of the cut away parts, said plates having further 110 cut away portions, tongues on the plates overlapping and sliding in the last mentioned cut away portions, pins on the cut away portions, said tongues having slots slidably receiving the pins, and resilient 115 means between the plates for normally keeping the same separated, substantially as described.
